Specification for Design.

Patented June 4, 1918.

Application filed February 16, 1918. Serial No. 217,707. Term of patent 3½ years.

To all whom it may concern:

Be it known that I, EDMUND BRUDER, a citizen of the United States, residing at Chicago, in the county of Cook and State of Illinois, have invented a new, original, and ornamental Design for the Casing of a Dispenser for Grit-Soap and the like, of which the following is a specification, reference being had to the accompanying drawing, forming a part thereof.

Figure 1 is a front elevation of a dispenser for grit soap and the like, showing my new design. Fig. 2 is a side elevation of the dispenser.

I claim:

The ornamental design for the casing of a dispenser for grit soap and the like, as shown.

EDMUND BRUDER.
